ELECTRICAL APPARATUS

Application filed March 30, 1925. Serial No. 19,369.

The present invention relates to electrical apparatus having to do with the control of electrical circuits and particularly with the control of radio circuits.

5 One of the principal objects of the invention is to provide means for concurrently varying the selectivity or decrement of one or more groups of coupled circuits.

Still a further object is to provide means 10 for eliminating or reducing the effects of undesirable or stray waves, such as atmospheric disturbances or shocks, upon electrical apparatus.

Further objects of the invention will be 15 apparent from the following description when taken in connection with the accompanying drawings, in which—

Fig. 1 is a diagrammatic view of a receiving apparatus embodying the present invention; and

Fig. 2 is a detail view illustrating certain features of construction of Fig. 1.

While the present invention is capable of embodiment in numerous forms, there is illustrated herein a preferred embodiment of the same, in which 20, 21 and 22 designate vacuum tubes or electron discharge devices of the audion type, each having a heated electron discharge cathode or filament 23, a grid 24 or input terminal 24 and a plate or output terminal 25. The electron discharge devices or tubes 20 and 21 are herein employed for amplifying the electrical oscillations received thereby, and the electron discharge device or 35 tube 22 is employed as a detector for translating radio frequency energy oscillations or signals into audio frequency energy oscillations or signals. It is not at all essential that the detector should be of the vacuum tube 40 type, as satisfactory results may be obtained with a crystal or other type of detector.

Heating current for the filaments 23 is supplied from the source of current 26 through suitable conductors 27 and 28, and each filament may be provided with a resistance 29 to regulate the flow of current therethrough. The conductor 27 connected with the negative side of the battery or source of current 26 has been indicated by a heavy line and 45 may be termed the common or negative side

of the apparatus. Input and output circuits are connected respectively with the input terminals or grids 24 and the output terminals or plates 25 of each of the vacuum tubes. The output circuit of the vacuum tube 20 is in 55 energy transmitting relationship with the input circuit of the tube 21, and the output circuit of the latter is likewise in energy transmitting relationship with the input circuit of the tube 22, so that the tubes 20, 21 and 22 are thus said to be connected in cascade. Electrically connected with input circuit of 60 the first vacuum tube 20 is a receiving or antenna circuit 30 which may be provided with the usual antenna and ground connections. 65

The antenna or receiving circuit 30 is connected with the input circuit of the first tube 20 and the output circuit of each tube is connected with the input circuit of the next succeeding tube through the medium of transformers 31, 32 and 33 which will now be described. The primary winding of each transformer is herein illustrated as comprising a pair of coaxial coils 34 and 35 which coils are spaced apart and in non-inductive relationship with one another, that is, they are wound so that their electrical effects are in opposition to one another. The coils 34 and 35 of the primary are preferably wound upon 70 a control tube 36 as shown in Fig. 2. Wound upon a suitable tube or frame 37 surrounding the tube 36 is a secondary winding 38 which is disposed intermediate the coils 34 and 35 of the cooperating primary winding. Coils 34 and 35 of the primary winding are preferably 75 of an equal number of turns and each have an inductive effect upon the secondary winding 38 but in opposite directions. The control tube 36 carrying the coils 34 and 35 of the primary winding is preferably mounted 80 for longitudinal axial movement whereby the coils 34 and 35 may be moved simultaneously within the secondary winding 38, and in this manner the relative inductive effects of 85 the coils 34 and 35 upon the secondary winding 38 may be varied to any desired extent. For example when the tube 36 is moved to the right so that the coil 34 is opposite the secondary winding 38 then there is a maximum 90 degree of coupling of the primary and sec- 95 ondary windings. When the tube 36 is moved to the left so that the coil 35 is opposite the secondary winding 38 then there is a minimum 100 degree of coupling of the primary and sec-

ondary windings in one direction, and likewise when the coil 35 is moved opposite the winding 38 then there is a maximum degree of coupling in the opposite direction. Various degrees of coupling between the maximum in one direction and the maximum in the other direction may be obtained by causing the secondary winding to assume various positions between the coils 34 and 35, and when the inductive effect of these coils upon the secondary winding 38 is nearly equal or balanced then the coupling is of nearly zero value so that there is almost no transfer of energy from the primary to the secondary winding. At this time the transformer may be said to possess its greatest selectivity or in other words its minimum decrement.

The construction and arrangement of the primary and secondary windings of the transformers 32 and 33 are substantially the same as that of the transformer 31. However the several transformers are so interconnected that the variation in coupling of the several transformers may be accomplished simultaneously or concurrently, and also equally if desired. This may be accomplished by mounting all the primary windings upon a single control tube 36, as illustrated, whereby the primary windings may be moved simultaneously relative to the secondary windings, or this may be accomplished in any other convenient manner.

In the circuit arrangement illustrated in Fig. 1 each of the secondary windings 38 is connected in the grid or input circuit of a vacuum tube or electron discharge device, said input circuit extending from the grid 24 through the secondary winding 38 to the common or negative conductor 27. The input circuits are preferably provided with adjustable condensers 39 whereby the several input circuits may be tuned to the same frequency. The primary windings of the transformers 32 and 33 are connected in the output circuits of the tubes 20 and 21 the circuits extending from the plate terminals 25 through fixed condensers 41, coils 34 and 35 of the primary, and thence to the negative conductor 27. Suitable plate voltage is impressed upon the output circuits of the tubes 20 and 21 by means of the conductors 42 connected with the positive terminal of battery 26-43-44, the conductors 42 being provided with suitable choke coils 45 which offer a high impedance to the radio or high frequency current, and thereby cause the same to flow through the primary windings of the transformer instead of passing off through the conductors 42. The output circuit of the detector tube 22 extends from the plate terminal 25 through a telephone or translating device 46 to the positive side of the battery 26-43.

The operation of the present invention may be explained by reference to Fig. 1. As-

suming that the secondary winding 38 is in the mechanically midway or central position between the primary windings 34 and 35, and further that high frequency currents of a given frequency and of continuous and sustained character are being impressed upon the primary circuit, it will be seen that the flow of this high frequency current in the first coil 34 of the primary winding acts inductively upon the nearest part of the secondary winding 38 to induce a current therein, as indicated by the arrow 50. This induced current may be assumed to travel from left to right through the secondary winding towards the grid 24 in order to impress its effect upon the grid, but owing to the length of the secondary winding a certain length of time is consumed in moving through the winding 38. The impressed high frequency currents after they leave the first primary winding 34, pass to the second primary winding 35 causing the latter to act upon the nearest or right hand end of the secondary winding 38, as indicated by the arrow 51, to induce a current therein which is in opposition to the current induced by the primary winding 34.

However, owing to the fact that the current induced in the secondary winding by the first primary coil 34 must pass through the length of the secondary 38 and is necessarily retarded somewhat by the impedance of this winding, the current induced in the secondary winding by the coil 35 predominates for the time being and the effect thereof is impressed upon the grid 24. To establish an electrical balance between the currents induced in the secondary winding by the coils 34 and 35, the primary windings may be moved to the right, out of the mechanically central position, so as to increase the inductive effect of coil 34 and decrease the effect of coil 35 upon secondary winding 38. In this manner an adjustment may be made such that the current flowing through the two primary coils 34 and 35 has no effect upon the grid 24, and the primary and secondary windings of the transformer are then said to be in neutral or zero coupling position. In the above discussion it has been assumed that the current impressed upon the primary winding is of a given frequency and wave character, as for example, the current that is received from a broadcasting station which is generally of a continuous and sustained character. The current received from such a station has more or less uniform characteristics, that is, the wave form, the potential, and other factors are of a uniform nature. Such waves when impressed upon the primary winding of the present invention induce energy oscillations or currents in the secondary winding, but owing to the impedance of the secondary circuit and other electrical factors, the phase relations of the current and voltage induced

in the secondary winding are altered, that is to say, the power factor of the induced current is not the same as the power factor of the current impressed upon the primary winding.

Should high frequency currents of other characteristics than the current above referred to be impressed upon the primary winding, as for example currents having

10 other frequencies, or irregular frequencies or irregular wave forms as in the case of atmospheric disturbances, then the impedance of the secondary winding with respect to these latter currents is not the same as it is

15 for the currents of given frequency and characteristics as first referred to, and the secondary winding will therefore have different zero or neutral coupling positions for currents of different characteristics. In opera-

20 tion the primary and secondary windings are so adjusted as to assume zero or neutral coupling position for the undesirable or so-called disturbing electrical currents, as for example, the atmospheric disturbances. In

25 this position the windings are not in neutral or zero coupling position with respect to the electrical oscillations or currents of desirable characteristics and the latter are therefore impressed upon the grid 24.

30 From the foregoing it will be apparent that energy oscillations or currents of different characteristics impressed upon the primary winding are affected unequally in transmission to the secondary winding, and conse-

35 quently one may adjust the apparatus so as to eliminate or suppress the effect of the currents of undesirable or disturbing characteristics upon the grid circuit. Stated in other words, the apparatus herein described may be

40 said to function as a selector for selecting the waves of the desired characteristics and, comparatively speaking, suppressing the effect of the waves of undesirable characteristics to an extent depending upon the ad-

45 justment of the apparatus. Although waves of various frequencies and characteristics are picked up by the antenna circuit 30 and impressed upon the transformer 31, the windings of the latter may be so adjusted that

50 waves having the desired characteristics have a maximum effect upon the grid of vacuum tube 20 whereas the effect of waves of different and undesirable characteristics is suppressed to say, for example one-half of their

55 original value. Energy waves or oscillations impressed upon the grid and input circuit of the first vacuum tube 20 are amplified in a manner well understood in the art and such amplified waves are impressed upon the

60 primary circuit of transformer 32. Assuming that here also the waves of undesirable characteristics are suppressed to one-half their value, as compared with the waves of the desired characteristics, it will be seen

65 that the effect of the former upon the grid

of vacuum tube 21 has been reduced to one-fourth the effect of the latter. And likewise the disturbing waves of undesirable characteristics are also suppressed by the transformer 33 so that their effect upon the

70 grid of detector tube 22 is now but one-eighth of their original value as compared with the effect of the waves of desirable characteristics. The foregoing theoretical considera-

75 tion appears to be consistently borne out by the results which have been obtained in practice, but it is to be expressly understood that I do not wish to be limited thereby as the invention is in no way dependent upon an accurate understanding of the theory and should not be construed as limited by such considerations.

While the invention has been herein de-

scribed and illustrated in its application to a receiving apparatus for amplifying and

detecting radio frequency currents, it should be understood that it is not limited to this precise application but is equally useful in apparatus employing low frequency trans-

formers as, for example, in the amplification of audio frequency currents. Also it should be understood that the invention is not limit-

ed to the precise arrangement of coaxial primary and secondary windings herein de-

scribed nor need the separate coils of the primary winding have an equal number of turns, since any construction and arrange-

ment of the parts capable of producing the results herein described is considered as com-

ing within the scope of the present invention.

While the form of apparatus herein de-

scribed constitutes a preferred embodiment

of the invention, it is to be understood that the invention is not limited to this precise form of apparatus, and that changes may

105 be made therein without departing from the scope of the invention which is defined in the appended claims.

What is claimed is:

1. In an apparatus of the character de- 110

scribed, several pairs of coupled circuits con-

115 nected for concurrent operation in cascade, and means for concurrently varying the coupling relation of said pairs of circuits, each of said pairs of coupled circuits having inductively coupled primary and secondary

120 windings, and said means having a single movable member to which a winding of each

pair is securely fixed for bodily varying in

125 unison the relative positions of the primary and secondary windings of said pairs.

2. In an apparatus of the character de-

scribed, several pairs of coupled circuits con-

130 nected for concurrent operation in cascade, one of said pairs of circuits comprising a grid

125 circuit having a secondary winding therein

130 and a grid connected with one end of said sec-

ondary winding, a primary circuit having a

135 primary winding therein said primary wind-

ing comprising opposed relatively fixed coils

- each adapted to be inductively coupled with said secondary winding, and means for concurrently changing the coupling relation of said pairs of circuits to cause at the grid end 5 of said secondary winding an appreciable time lag between voltage induced in the secondary winding by one of said coils and the voltage induced in said secondary winding by the other of said coils.
- 10 3. In an apparatus of the character described, a pair of coupling circuits, and means for varying the coupling relation of said circuits comprising coupled primary and secondary windings in said circuits, one 15 of said windings having spaced relatively fixed coaxial coils wound in series to produce opposed inductive effects, and the other winding comprising a coil inductively associated with both said coaxial coils, and means 20 for relatively moving said primary and secondary windings coaxially.

In testimony whereof I hereto affix my signature.
